UNITED STATES PATENT OFFICE.

CHARLES F. MARKHAM, OF PROVIDENCE, RHODE ISLAND.

PIN.

1,029,205.

Specification of Letters Patent. Patented June 11, 1912.

Application filed January 4, 1912. Serial No. 669,834.

To all whom it may concern:

Be it known that I, CHARLES F. MARKHAM, a citizen of the United States, and resident of the city of Providence, in the county of Providence and State of Rhode Island, have invented certain new and useful Improvements in Pins, of which the following is a specification.

This invention relates to pins, and has for its object to provide a separate and independent catch member of the class adapted to receive and retain the pointed end of the pin-stem, the same being formed with a short base plate extending over the edges of which the edge of the front plate or body portion of the pin is rolled to retain the catch member in the back of the front plate, thus eliminating the necessity of using solder for this purpose.

20 A further object of the invention is to turn or curve the edges of the base plate of the catch member slightly upward from the plane thereof, whereby when said base plate lies against the back of the front plate the roll of the latter will engage and interlock with said turned-up edge firmly securing the said member in position. Then again, in rolling the edge of the front plate over the turned up edge of the base plate the pressure 25 of the roll springs this edge downward and the natural resiliency of the metal also serves to assist in retaining the same in position.

With these and other objects in view, the invention consists of certain novel features of construction, as will be more fully described and particularly pointed out in the appended claim.

Of the accompanying drawings: Figure 40 1— is a central sectional side elevation of a pin having my improved catch member mounted therein. Fig. 2— is an enlarged perspective view of my improved catch member. Fig. 3— is a sectional side elevation 45 of my catch member. Fig. 4— is an enlarged plan view of the underside of a pin showing my improved construction of catch member connected to the body thereof by rolling the edges of the latter over those 50 of the former. Fig. 5— is a section on line 5—5 of Fig. 4 showing the catch member as secured in position by the rolled edge of the front plate. Fig. 6— is a section on line 6—6 of Fig. 4 showing the rolled edge of 55 the front plate as engaging and forcing downward the turned up edge of the base

plate whereby the spring of the latter assists in retaining the same in position.

Referring to the drawings, 1 designates the body portion or front plate of the ordinary cuff or beauty pin which front plate is preferably constructed of thin sheet metal.

The essential feature of my present invention is the forming of the catch member 2 independent of the front plate and from a 65 piece of sheet stock bent to form a base plate 3 whose width is substantially that of its length. This qualification is included to distinguish from the usual back plate which extends the full length of the pin body. The 70 edges 4 of this base plate are preferably turned upward from the normal plane of the plate for the purposes hereinafter fully set forth. A narrow neck portion 5 extends upwardly from the rear portion of 75 this base plate and has a forwardly extending curved hood 6 which is for the purpose of receiving and retaining the pointed end 7 of the pin-stem 8.

In assembling the parts of this pin, the 80 base portion of the catch member is preferably set to rest against the rear face 10 of the front plate, the edge of the latter being then rolled over the upturned edges of the base plate thereby interlocking the edges 85 of the base plate with those of the front plate. Then again, it is found in practice that the pressure of the roll 9 at the point 11 on the base plate, see Fig. 6, has a tendency to force and spring the turned up edges 90 downward whereby the natural resiliency of the metal further assists in retaining the plate in position. Then again, as illustrated in Fig. 6, the roll at the point 12, just forward of the turned up portion of the 95 flange, is carried downward below or beyond this turned up edge forming an additional barrier or stop to prevent the member from moving forward from the end of the body portion where it is designed to be retained. 100

In forming a pin of my improved construction of precious metal, such as gold, silver, platinum, or the like, it will be seen that the body portion may be constructed of extremely thin material stiffened to the desired degree by suitable ornamentations and also by the roll around the edge. Then by forming the joint and catch members independently and of separate stock, they may also be formed of precious metal but of 110 heavier stock, in order to provide the strength required for such members. Then

by providing each of these members with a flange or base plate and securing them firmly in position to the back of the front plate by rolling the edges of the latter over those of the former, the use of solder or other expensive or objectionable fastening methods is effectually obviated.

Another feature of this construction is that I entirely obviate the necessity of using 10 the usual whole back plate, which extends the full length of the pin and to which the separate joint and catch members are ordinarily attached. By this construction and the elimination of this back plate, the 15 entire pin, including both the joint and catch members may be formed of precious metal of the minimum thickness at the same time forming each individual part of sufficient thickness to stand the strain required 20 of it.

I claim:

In a pin, a front plate, an independent catch member having a pin point receiving portion and a base plate integral with said portion, the edges of said base plate being 25 turned slightly upward from the plane of said plate, said plate resting upon and being supported against the inner surface of the front plate, and the edges of said front plate being rolled over the said upturned 30 edges of said base plate whereby the latter is interlocked with the roll of the front plate near the end of the pin body to rigidly retain said member in position therein.

In testimony whereof I affix my signature 35 in presence of two witnesses.

CHARLES F. MARKHAM.
